UNITED STATES PATENT OFFICE

2,602,573

WRISTBAND FOR WATCHES

Albert A. Herbst, Wichita, Kans.

Application April 5, 1948, Serial No. 19,039

3 Claims. (Cl. 224—4)

1

My invention relates to an improvement in wrist bands that are designed, primarily for holding watches; although the device might be used as an ornamental bracelet.

A further object of the invention is to provide a wrist band having edges that have the general appearance of being hand laced and the edges are a material commonly known as piping, which consists of a strip of textile material, one edge of which is provided with a beading of suitable material, such as plastic material or a thickened edge woven as a part of the textile material or as a series of metallic or other material, beads and the like, any of which would form an ornamental edge around the wrist band.

A further object of the invention is to provide a wrist band of the kind mentioned having the ornamental appearance of the kind mentioned and yet being very simple in construction, extremely durable and inexpensive to make.

These and other objects will be more fully explained as this description progresses.

Now referring to the accompanying drawings in which similar numerals of reference designate the same parts throughout the several figures of the drawings.

Fig. 1 is an edge view of a wrist band in which my invention is included.

Fig. 2 is a side view of the wrist band shown in Fig. 1.

Fig. 3 is a plan view of the wrist band, the band being in a flattened position as it would be, prior to the forming of the wrist band into the shape shown in Fig. 1, parts of the wrist band are broken away for convenience of illustration.

Fig. 4 is a longitudinal detail sectional view through the wrist band, the view being as seen from the line IV—IV in Fig. 3 and looking in the direction of the arrows.

Fig. 5 is a perspective view of the wrist band that is made up in the spring clamping type of band.

Fig. 6 is a plan view of the flexible type of band, having a buckle fastening.

In the drawings, Figs. 1 to 5, inclusive, is shown the spring type of wrist band which comprises an upper facing element 10 and a lower facing element 11, the facing elements 10 and 11 are made of any suitable material, preferably leather that are substantially the same size and shape and are superimposed, one upon the other. Between the facings 10 and 11 is positioned a strip of spring steel material 12, which is narrower than, and extends substantially from end to end of the facing elements 10 and 11. The

2

wrist band is provided with an edging, commonly known as piping, which consists of a textile attachment and supporting, strip of material 13 having an edging E formed along or attached to one edge of the textile supporting strip 13. As shown in the drawings the edging E consists of a flexible plastic bead having diagonally or spirally positioned and alternate, contrasting, colored portions 14 and 15. The textile supporting portion 13 of the piping is positioned between the outer edge portions of, and extending entirely around and between the facing elements 10 and 11 with the edging portion E closely and tightly abutting the edges of the facing elements 10 and 11. The several above mentioned elements being assembled as described, a row of stitching 16 is placed along the edges of the facing elements 10 and 11, whereby the edges of the facing elements 10 and 11 and the textile strip 13 are all tightly fastened together with the edging E abutting the edges of the facings 10 and 11. Because of the diagonal positioning of the alternating colored spaces 14 and 15, the edges of the facings 10 and 11 appear to be laced together and thereby gives the band the appearance of being a much more expensive article than it really is.

While the wrist band as shown and described has the appearance of the edges being laced, it is obvious that the edging E might be made in the form of beads or other shapes of ornamentation that will add to or give the wrist band a large variety of ornamental characterizations.

In Fig. 6 the wrist band is shown as not having the spring steel element 12 contained therein and the band is therefore pliable and has no spring action as above described, therefore one end of the band is provided with a buckle and a looped keeper 18 to receive the other end of the wrist band which is provided with a series of holes 19 to receive the tongue 20 of the buckle 17 for buckle fastening in the usual manner as will readily be understood. The ends of the band having been buckled together as above described, the remaining free end of the band may be slipped through the looped keeper 18 in the usual manner.

As above mentioned, this band is designed primarily for holding watches, therefore the outer facing element 10 is provided with a pair of looped strap watch holder elements 21 and 22. The ends of each loop strap are passed through their respective slits 23 or 24, and positioned between the facing elements 10 and 11, or between the facing element 10 and the textile strip 13 and

the side edges of one end of the loop elements 21 and 22 are caught in the stitching 16 to rigidly bind and hold that end of the loop elements 21 and 22 in place as above described.

The other end of each loop element 21 and 22 is left free so that it may be pulled from and reinserted through the slits 23 and 24 may be threaded through holder loops 25 and 26 on the sides of the watch 27 and the free ends of the loop elements 21 and 22, then reinserted through 10 their respective slit 23 or 24, whereby the watch 27 is substantially held on the wrist band.

While the wrist band, as shown, in the drawings, and described in the foregoing specification, is probably the preferred form of the device, it is to be understood that such modifications may be employed as lie within the scope of the appended claims without departing from the spirit and intention of the invention.

Now having fully shown and described my invention, what I claim is:

1. In a wrist band of the kind described; said wrist band comprising, in combination, a pair of facing elements, said facing elements varying in width at selected points between the ends thereof and being substantially the same shape and size and superimposed, one over the other; a piping, said piping having a carrying element of uniform width for said piping, said carrying element being less than one half the width of 30 said facings at their narrowest width and being positioned between and extending around the sides and ends of said facing elements with the said piping extending along and beyond the edges of the said facing elements to expose an edge 35

thereof, said exposed piping edge having alternately light and dark colored portions to give the appearance of the edges of the facings being laced together and means for holding the band in a looped formation as a means of retaining the band on the wrist of the wearer of the band.

2. In a wrist band of the kind described; the combination defined in claim 1, said combination being further characterized by one of said facing elements having loop means thereon that are attachable to an article for holding said article on the band.

3. In a wrist band of the kind described; the combination defined in claim 1, said combination being further characterized by the said means for holding the band in a looped formation being a curved spring element interposed between the two said facing elements.

ALBERT A. HERBST.
